ROLLING WHEEL TOY

Dominic M. Desiderio, McKees Rocks, Pa.

Application July 23, 1949, Serial No. 106,379

1 Claim. (Cl. 46—47)

1

This invention relates generally to toys and, more particularly, to a toy of the nature of a perpetually rotating wheel on a track.

An object of the present invention is to provide a wheel having an axle mounted for to and fro rolling motion on a track, simulating perpetual motion, for fascinating small children.

Other objects and advantages of the present invention will become apparent from a study of the following description taken with the accompanying drawing wherein:

Fig. 1 is a perspective view of a somewhat perpetually rotating wheel type of toy embodying the present invention, and

Fig. 2 is a perspective view of a modified form of track having a different shape than that shown in Fig. 1.

Referring more particularly to Fig. 1, numeral 1 denotes a base having four vertically extending holes adjacent its corners into which there are inserted legs 2a and 3a of tracks 2 and 3. The tracks have substantially horizontally extending portions 2b and 3b which are curved with the lowest point at the center and the highest points at the ends. The tracks are preferably arcs of a circle of the order of 33 inches in radius. A wheel 4 has integrally secured to the center thereof an axle 5 having portions extending from opposite faces of the wheel and which are adapted to roll on tracks 2 and 3.

In operation, the axle 5 is laid near either end of the tracks 2 and 3 and then released. In view of the downward inclination of the tracks toward the center, the axle will roll in a direction towards the center and, as the result of its momentum, will pass beyond the center of the tracks while losing speed, reaching a point near the opposite ends thereof where it will slow down to a stop and then will roll in the opposite direction. Its momentum will again cause rolling beyond the center and almost up to the initial point from which the wheel was released, where it will again stop and rotate in an opposite direction but slightly short of the first point it reached due to rolling friction. Thus the wheel will continue to roll back and forth on the track with shorter ranges of travel and slower speed until finally it will stop at the center of the tracks which is the lowest point.

Fig. 2 shows a modification of the track shown in Fig. 1. Only one track is shown, although it will be understood that a duplicate one will also be used in the manner shown in Fig. 1. The substantially horizontal portion of the track comprises three straight segments 6a, 6b and 6c. Segments 6a and 6c are straight and are inclined downwardly from the ends of the track to the depth of the central straight horizontal segment 6b, which depth may be of the order of $\frac{1}{16}$ inch. The length of segments 6a and 6c may be of the

2

order of $2\frac{3}{4}$ inches each and that of 6b, 2 inches. It should be understood, however, that these dimensions are merely exemplary and not limiting. With such dimensions it is possible to obtain up to about 15 rolls of the wheel, to and fro.

Likewise, other modifications will be readily suggested to those skilled in the art. For instance, it is possible to use objects other than wheels, such as cutouts of acrobats or animals. Also, it is possible to use a single track of the type shown in Fig. 1 or Fig. 2 with two wheels interconnected by an axle, wherein the axle is adapted to roll on such single track provided the axle is grooved peripherally to prevent rubbing of faces of the wheels on the track.

Thus it will be seen that I have provided a relatively simple and inexpensive toy giving the appearance of a perpetually rotating wheel and providing entertainment, especially to small children.

While I have illustrated and described certain specific embodiments of my invention, it will be understood that these are by way of illustration only, and that various changes and modifications may be made within the contemplation of my invention and within the scope of the following claim.

I claim:

A toy of the nature of a perpetually rotating wheel comprising a base having four vertically disposed holes, a pair of wire-like track members each having vertically downwardly extending leg portions, the ends of which are adapted to be inserted in said holes and a substantially horizontally extending portion, said horizontally extending portions being arcuate and having a radius of the order of 33 inches, and a wheel having smooth cylindrical axis portions extending from opposite faces thereof, said axle portions being adapted to roll on said horizontally extending portions of the track members many times as the result of initial placement of the axle portions on one of the ends of said horizontally extending portions of the track members.
